The ornamental design for a small desktop docking station, as shown and described.

DESCRIPTION

FIG. 1 is a top front right side perspective view showing my new design;

FIG. 2 is a top front left side perspective view thereof;

FIG. 3 is a bottom perspective view thereof;

FIG. 4 is a top elevational view thereof;

FIG. 5 is a bottom elevational view thereof;

FIG. 6 is a front elevational view thereof;

FIG. 7 is a rear elevational view thereof;

FIG. 8 is a right side elevational view thereof; and,

FIG. 9 is a left side elevational view thereof.

In the drawings, the claimed design is defined by the solid lines and shaded surfaces; the unshaded surfaces shown between the solid lines and the broken lines form no part of the claim.

The broken lines in the drawings depict portions of the small desktop docking station that form no part of the claimed design.
